UNITED STATES PATENT OFFICE

2,305,685

BUILDING CONSTRUCTION

Thomas J. Foster, Ridgewood, N. J.

Application February 2, 1939, Serial No. 254,288

11 Claims. (Cl. 189—1)

This invention relates to low cost heat and sound proof buildings constructed of prefabricated panels made of fire resisting materials, as described in my patents, Nos. 1,825,346; 1,964,728; 1,989,798; 2,001,605; 2,040,732; 2,069,755 and 2,070,479, and aims to improve the heat and sound proof properties without increasing the cost of construction.

In steel frame buildings as heretofore constructed, the floors and walls are supported directly by the metal frame, with no adequate sound deadening means intervening, and noise and mechanical vibrations originating on one floor of a building readily penetrate to all parts of the building.

My invention provides for completely insulating each floor from the supporting beams and girders, and from the ceiling and walls beneath, and for insulating the walls from the floor beams, thereby preventing noises and vibrations in one floor area from being communicated through the walls and metal frame into other parts of the building.

Other aims and advantages of the invention will appear in connection with the description of the illustrative embodiments thereof shown in the accompanying drawings, wherein

Fig. 1 is a vertical cross-section through a portion of a building embodying the invention showing a supporting I-beam and portions of the floor slab and wall and ceiling panels supported thereby;

Fig. 2 is a similar view of an exterior wall and floor and ceiling construction;

Fig. 3 is a cross-section of a part of the ceiling panel on the line 3—3 in Fig. 1;

Figs. 4 and 5 are views similar to Figs. 1 and 2, respectively, illustrating another type of panel; and

Figs. 6 and 7 are vertical cross-sections of another modification of the floor slab and supporting beam, Fig. 6 being taken on the line 6—6 of Fig. 7, and Fig. 7 being taken on the line 7—7 of Fig. 6, respectively.

In the construction illustrated in Figs. 1, 2 and 3, the floors are made of unitary panels 11, each having two body layers 12 of cementitious material, preferably separated by a middle layer of heat and sound insulation 13 and strengthened by metal reinforcement comprising transverse channel shape members 14 and wire mesh 15 near the faces of the panels or equivalent reinforcing means, as described in my prior and copending patents. The top face may form the floor finish, in which case it is preferably made

5 of wood or other continuous sheet material 16 presenting a smooth surface of any desired appearance and wearing qualities. Fastenings 17, cast into the upper body layer 12 as described in my copending application Ser. No. 252,650 hold the top face in place and firmly secure it to the body layer to form a unitary part of the panel. A layer of waterproof material 18, is advantageously placed between the cementitious body layer 12 and the under side of the floor finish to protect the latter from the wet cement during the process of making the panel, and to assist in deadening the sounds and vibrations to which the floor may be exposed.

10 15 The floor panels 11 are supported at their edges on the top flanges of the floor beams 19, Keldur (a rubber like material), rubber or cork strips 20 being inserted between the under faces of the panels and the top faces of the beams 20 to insulate the floors from the beams against passage of sounds and mechanical vibrations in either direction, thereby preventing noise and disturbance on any floor from getting into the metal frame of the building. The joints between 25 adjacent floor panels may be filled with any suitable plastic material 21 which will prevent entrance of moisture, thereby connecting the panels to form a continuous floor slab.

20 25 In all except very low cost buildings a top flooring is desirable, and preferably a continuous layer of felt 22 or other sound deadening material is spread over the floor slab, and the top floor 23, which may be wood, tile, or plastic material, is laid upon this cushion and secured by nails, cement, or other suitable means. Such a floor construction provides an effective barrier to the passage of sound through the floor slab and into the frame of the building.

30 35 The partition panels 25 rest at their lower edges either directly on the floor slab or on cushion blocks 26 supported on the slab, usually over the beams, and thus are insulated from the beams thereby and by the materials of the panels and the sound cushioning strips 20. The usual mop boards 27 and corner beads 28 may be provided, or other base trim, as desired. These partition panels may be formed as described in my copending application Ser. No. 252,650, and are preferably principally composed of body layers 31 separated by insulation 32 and connected by metallic transverse reinforcement 33 and sheet reinforcement 34 similarly to the floor panels. These partition panels may be made of a length to extend from the floor level to just 40 45 50 below the under faces of the flanged beams 19

supporting the next higher floor, being tied to the latter by metal straps 35 bent around the lower flanges of the beams and nailed or otherwise secured to wooden blocks 36 suitably embedded in the upper edges of the panels. The ends of the strips 35 are nailed or otherwise secured to blocks of wood or tough material 37 which rest upon the lower flanges of the beam 19 and serve to insulate the straps therefrom, these blocks in turn being held in place by the straps 35 and by the ceiling panels 38, as hereinafter described.

Preferably the ceiling panels comprise a layer of cast gypsum or other cementitious material 39, strengthened by continuous reinforcement 40, and stiffened by channel shape ribs 41, 43, of reticulated metal, the ribs being partly embedded in the gypsum layer as illustrated in Fig. 3. Wood blocks 42 may be inserted at spaced intervals between the flanges of the ribs 41, 43 to provide means to which the reinforcement 40 and rib flanges may be nailed before being embedded in the gypsum in the process of forming the ceiling panels.

The ceiling panels 38 are supported at their ends from the beams 19, below the floor panels and separated therefrom by a space 44 which may be left open or partly filled with loose dry insulating material such as spun glass, comminuted cork, mineral wool, asbestos fibre or other light weight, non-conducting material that can be spread, blown or laid in batts, as desired, so as to provide an insulating layer between the floor and ceiling. These ceiling panels may rest upon the lower flanges of the floor beams 19 but preferably are spaced above these flanges upon the blocks 37, which may be provided with notches or shoulders 45 to hold them against shifting unduly.

The spaces between the lower edges of the ceiling panels and the lower flanges of the floor beams are preferably closed by molded cornice strips 46, which may be secured to the blocks 37 by means of nails 47 or other fastenings, spacers 48 and strips 49 of felt or similar cushioning and sound deadening material being inserted between these cornice strips and the parts of the structure which they bear against.

These cornice strips overlap the upper ends of the wall panels 25 and cover the metal straps 35 and blocks 37 which secure them to the beams. If preferred, the metal straps may be secured to separate blocks instead of to those supporting the ceiling.

The outside wall construction shown in Fig. 2 comprises beams 50 upon which the edges of the floor panels 11 rest, and to which are secured blocks 51 for supporting the edges of the ceiling panels 38, nails 52 or adhesive being used for securing the blocks in place. The cornice 53 is secured to the blocks 51 by nails 54 or other suitable means.

In the outer wall construction shown in Fig. 2, the wall panels 55 are similar to the partition panels except for the exterior finish 56 which is of weatherproof material, such as asbestos shingles, stucco or wood sheathing. The lower panels rest upon the sills or suitable foundation supports at their lower ends, and are secured to the floor beams 50 by lag screws 58, which engage in the blocks 59 provided for that purpose in the margins of the panels and clamp their upper edges to wood blocks 60, which in turn are supported upon the lower flange of the adjacent beam. The joints between the panels may be

closed by caulking, waterproof cement, or other suitable plastic material.

The modified floor and wall construction illustrated in Figs. 4 and 5 comprises floor beams 64 and walls beams 65 upon the top flanges of which the floor panels 66 are supported, cushion strips or blocks 67 being placed between the lower edges of the panels and the beams as in the construction shown in Figs. 1, 2 and 3. These floor panels may be of semi-fireproof construction as described in my prior patents.

The ceiling panels 68 are supported at their edges on blocks 69 which rest on the bottom flanges of the floor beams. Felt or other sound absorbing strips 71 are placed beneath the edges of the ceiling panels, between them and the supporting blocks 69, as shown. Nails 72, passing through the webs of the beams 64, 65, or an adhesive hold the supporting blocks 69 in place.

In the form of the invention illustrated, the ceiling panels comprise wood stiffeners 75, extending from edge to edge between the beams, and plaster board or other sheets 76 secured to the under faces of the stiffeners by cement, nails, or other suitable means, the sheets 76 being large enough to extend the full length and width of each panel. Over the tops of the stiffeners a layer of coarsely woven fabric 77, or chicken wire, coated or impregnated with metallic paint, is stretched and secured by cement or roofing nails.

This construction provides a light, stiff, fire-resisting ceiling, which has effective sound deadening properties, and adds nothing to the cost of the building. The beams may be additionally protected by plaster boards strips 78, secured to the blocks 69 by any suitable means.

The partition panels 80 are preferably supported on the floor slab, as in the construction shown in Fig. 1, resting upon cushion blocks 81, and with the space between their upper edges and the floor beams 64 filled with plastic cement or sound deadening material. Metal strips 83, nailed or otherwise secured to the blocks 36 in the panels, and to the ceiling supporting blocks 69, serve to position the upper edges of the wall panels centrally of the floor beams, as shown in Fig. 4.

The wall panels 87, 92 are made in accordance with my copending application Ser. No. 252,650, and their exterior surfaces may be painted or covered with weatherproof material 95 such as stucco, the joint between the lower and upper panels being closed with cement 94 or other hardened plastic material, as illustrated in Fig. 5.

In the modified floor construction illustrated in Figs. 6 and 7, the floor panels are built up of wood joists 102 and tongued and grooved floor boards 101, cemented or nailed together and the ends of the joists are notched to receive the top flanges of the steel floor beams 103 upon which they rest, cushion blocks 104 of keldur or other sound insulating and vibration absorbing material being placed between the notched ends of the joists 102 and the tops of the beams. Metal inserts 105 may be driven into the ends of the joists near the inner corners of the notches to prevent splitting.

Preferably the floor panels are held in place by clips or braces 106 attached to the floor joists and projecting under the edges of the upper flanges of the floor beams, cushion blocks 107 being inserted between the adjacent faces of the beam flanges and braces to absorb sounds and vibrations. This construction permits ducts 108 for electric wires and telephone circuits to be dis-

posed in the spaces under and between the floor boards and joists and secured to the latter by staples 109, clips or other fastenings. Holes 110 may be left in the webs of the floor beams at convenient intervals to facilitate the placing of these ducts.

The ceiling panels illustrated in Figs. 6 and 7 are composed of non-combustible sheet material 111 to which stiffening members 112 of wood are secured by adhesive or other fastening means to form rigid unitary ceiling members having flat under sides to provide an acceptable finish for concealing the under sides of the floor panels. Sufficient space is left between the floor panels and ceiling panels to receive a layer 113 of mineral wool or other insulating material having sound deadening characteristics. These ceiling panels are supported along their edges upon blocks 114 of wood or other heat insulating and sound deadening material, which in turn rest upon the lower flanges of the steel floor beams. Cover strips 115, of wood or composition are nailed to the blocks 114 and ceiling panels, as shown in Fig. 6, to make an attractive finish. The cover strips and under faces of the ceiling panels may be painted, sprayed, or otherwise decorated or finished in keeping with the walls and trim in the building.

The floor and ceiling panel structure illustrated in Figs. 6 and 7 is light in weight and cheap to manufacture and install, and may be made strong enough for residences and small shops and stores, for which it is suitable. Although not fireproof, the ceiling is fire resisting, and the insulation is sufficient to protect the floor joists above from ordinary fires originating in the lower story.

One advantage of the construction embodying separate floor and ceiling panels is the opportunity for fastening electric ducts and cables to the bottom of the floor panels both for ceiling lights and for distributing electric current for lighting, power and communication purposes. The webs of the beams will preferably be provided with sufficient spaced holes to enable these ducts and circuits to be carried across the panels as desired.

In erecting the building, after the floor beams have been placed, the floor panels are raised to position and laid upon the cushion blocks or strips 20 and fastened to the upper flanges of the beams. Next the ceiling panels are raised from below and inserted one edge at a time in the space underlying the floor between the webs of the adjacent beams, and the spaced blocks 31 are inserted from below and then secured in place by nailing them together. If insulation is used in the space 44 between the floor and ceiling panels, it is inserted with the ceiling panels which support it. The partition panels are erected next and the cornices are placed last, as will be readily apparent to those familiar with this type of building construction.

My invention provides a light weight fire resisting floor and wall structure with a crack-proof ceiling that absorbs most of the vibrations and noises originating on the floor, and prevents them from reaching other parts of the building through the frame and walls. It may be readily adapted to the art of prefabricated and low cost buildings, principally constructed of fire resisting materials, and designed to provide modern housing facilities on a large scale.

The low cost of the floors and walls made with panels embodying the invention, and the low cost

of the steel frame fabricated as shown by my Patent No. 2,086,669, makes this fire resisting type of building less expensive for dwellings and small apartment buildings than the ordinary constructions with bricks and wood, to which it is superior from many standpoints, including better sound-proofing and fire resistance, less floor depth with a consequent less overall height and a smaller exterior surface of the building to maintain, reduced cost of interior maintenance by eliminating the cracks usually appearing in walls and ceilings of the lath and plaster type, and the lower cost of heating.

The invention is not restricted to the details of construction and use herein described, as modifications thereof to suit other conditions and uses will be obvious to those skilled in the art.

I claim as my invention:

1. In a floor construction for low cost buildings, a plurality of flanged metal beams, a series of self-supporting floor panels overlying the top flanges of said beams along their edges, cushion means between the top flanges of said beams and the overlying edges of said panels for supporting the latter, self-supporting ceiling panels spaced beneath said floor panels and overlying the bottom flanges of said beams, and sound insulating and supporting means beneath the edges of said ceiling panels and the bottom flanges of said beams, whereby said floor and ceiling panels are insulated from said beams.
2. In a floor construction for low cost buildings, a plurality of flanged metal beams, a series of self-supporting floor panels overlying the top flanges of said beams along their edges, cushion means between the top flanges of said beams and the overlying edges of said panels for supporting the latter, self-supporting ceiling panels spaced beneath said floor panels and overlying the bottom flanges of said beams, and sound insulating and supporting means between the edges of said ceiling panels and the bottom flanges of said beams, said floor panels comprising unbroken layers of heat and sound insulating material forming a substantially continuous protection against passage of heat and sound throughout the entire area of said floor, whereby said floor and ceiling panels are insulated from said beams and from each other.
3. In a floor construction having a plurality of flanged floor beams and a floor spanning said beams and supported by the upper flanges thereof, a series of ceiling panels spanning the spaces between the floor beams with their edges disposed between the top and bottom flanges thereof and supported from the latter, said panels comprising stiffening elements and a continuous layer secured together to constitute complete self-supporting units, and sound and vibration absorbing means positioned between said panels and the supporting flanges of said beams.
4. In a floor construction having a plurality of flanged floor beams and a floor spanning said beams and supported by the upper flanges thereof, a series of ceiling panels spaced below said floor and spanning the spaces between the floor beams with their edges disposed between the top and bottom flanges thereof and supported from the latter, said panels comprising stiffening elements and a continuous layer secured together to constitute complete self-supporting units, heat and sound insulation in the space between said floor and ceiling panels, and sound and vibration absorbing means positioned between said panels and the supporting flanges of said beams.

5. In a floor construction having a plurality of flanged floor beams and a floor spanning said beams and supported by the upper flanges thereof, a series of ceiling panels spaced below said floor and spanning the spaces between the floor beams with their edges disposed between the top and bottom flanges thereof and supported from the latter, said panels comprising stiffening elements and a continuous layer secured together to constitute complete self-supporting units, heat and sound insulation in the space between said floor and ceiling panels, and means positioned between said panels and the supporting flanges of said beams to retain said panels in spaced relation thereto.

6. In a floor construction having flanged floor beams, a series of ceiling panels spanning the spaces between the floor beams with their edges disposed between the top and bottom flanges thereof, said panels comprising stiffening elements and a continuous layer secured together to constitute complete self-supporting units, the transverse dimension thereof being greater than the clear space between the edges of the supporting flanges of said beams and less than the center to center spacing thereof, sound and vibration absorbing means positioned between the panels and the beam flanges to support the panels at their edges, and means disposed between said panel edges and the adjacent webs of the beams to maintain said panels centrally disposed between said beams.

7. In a floor construction having a plurality of flanged floor beams, a floor overlying said beams and supported thereby, a series of ceiling panels spanning the spaces beneath said floor between the floor beams with their edges disposed between the top and bottom flanges thereof, said panels comprising stiffening elements and a continuous layer secured together to constitute complete self-supporting units, the transverse dimension thereof being greater than the clear space between the edges of the supporting flanges of said beams and less than the center to center spacing thereof, and means positioned between the panels and the beam flanges to support the panels at their edges and maintain said panels centrally disposed between said beams, whereby said panels and supporting and spacing means may be erected from below after the floor has been put in place above said beams.

8. In a floor and ceiling construction having a plurality of flanged floor beams, a floor overlying said beams and supported thereby, a series of ceiling panels spaced beneath said floor and spanning the spaces between the floor beams with their edges disposed between the top and bottom flanges thereof, said panels comprising stiffening elements and a continuous layer secured together to constitute complete self-sup-

porting units, the transverse dimension thereof being greater than the clear space between the edges of the supporting flanges of said beams and less than the center to center spacing thereof, sound and vibration absorbing means positioned between the panels and the beam flanges to support the panels at their edges, and spaced means disposed between said panel edges and the adjacent beams to maintain said panels centrally disposed between said beams, whereby said panels and supporting and spacing means may be erected from below after the floor has been put in place above said beams.

9. In a low cost, heat and sound insulated building having metal floor beams, a substantially continuous floor comprising unitary self-supporting panels supported at their margins on said beams, and sound insulating means between said beams and panels, in combination with a ceiling spaced below said floor comprising unitary self-supporting panels supported at their margins adjacent said beams independently of said floor panels and between the top and bottom flanges thereof, providing a thin sound and vibration resisting floor construction.

10. A floor construction having a plurality of flanged metal floor beams and a floor spanning said beams and supported by the upper flanges thereof, and a series of ceiling panels spaced below said floor and spanning the spaces between the floor beams with their edges disposed between the top and bottom flanges thereof and supported from the latter, said panels comprising stiffening elements and a continuous layer of fire resisting material secured together to constitute complete self-supporting units, in combination with heat and sound insulation in the space between said floor and ceiling panels, and sound and vibration absorbing means positioned between said floor construction and the supporting flanges of said beams, thereby providing a thin quiet fire resisting floor for metal frame buildings.

11. A floor construction having a plurality of flanged metal floor beams and a floor spanning said beams and supported by the upper flanges thereof, and a series of self-supporting ceiling panels spaced below said floor and spanning the spaces between the floor beams with their edges disposed between the top and bottom flanges thereof and supported from the latter, in combination with heat and sound insulation in the space between said floor and ceiling panels, and sound and vibration absorbing means positioned between said floor construction and the supporting flanges of said beams, thereby providing a thin quiet fire resisting floor for metal frame buildings.

THOMAS J. FOSTER.
